UNITED STATES PATENT OFFICE.

WALTER B. PAYNE, OF ROCHESTER, NEW YORK, ASSIGNOR TO TODD PROTECTOGRAPH COMPANY, INC., OF ROCHESTER, NEW YORK.

CHECK WRITER.

Application filed September 22, 1920. Serial No. 411,911.

To all whom it may concern:

Be it known that I, WALTER B. PAYNE, a citizen of the United States, residing at Rochester, in the county of Monroe and State of New York, have invented certain new and useful Improvements in Check Writers, of which the following is a specification.

This invention relates generally to printing machines, and has particular reference to what are commonly known as check writers because of the fact that they are used mainly to write in the amounts of bank checks and similar instruments.

One object of the invention is to provide a satisfactory mechanism, separate from, but operating adjacent to the printing type and platen, to shred, break or otherwise disrupt the fibre of the material printed upon so that the ink used in printing may more readily penetrate the material and thereby increase the difficulty of erasing or altering the inscription.

Another object is to provide a mechanism such as just described, which will have certain advantages over prior devices of the kind. One advantage is that the improved mechanism is actuated to disrupt the paper or other material directly and positively by movement of the operating handle or corresponding prime mover of the machine. As a result, when the improvement is applied to machines constructed to print by rolling engagement of the type and platen the mechanism is driven in a fixed relation to the moving printing elements, and the paper is never subjected to a grinding action by the type and platen, or to any other strain or stress which might cause it to be torn or otherwise improperly mutilated.

With the above and incidental objects in view, the invention consists in the novel combination and arrangement of parts, a preferred form of embodiment of which is hereinafter described with reference to the drawings accompanying and forming a part of the specification and the features of novelty of which are pointed out in the appended claims.

In the drawings:

Fig. 1 is a partial top plan view of a machine having the invention applied thereto.

Fig. 2 is a left side view of the improved machine shown in Fig. 1.

Fig. 3 is a section on the line 3—3, Fig. 1.

Fig. 4 is a section on the line 4—4, Fig. 1.

Fig. 5 is a section on the line 5—5, Fig. 1.

Fig. 6 is a top plan view of the platen and paper-disrupting devices and their operating connections.

The machine to which an embodiment of the invention is shown applied in the accompanying drawings is of a type well known on the market, and which is shown and described in U. S. Letters Patent No. 1,138,330, issued May 4, 1915, to L. M. Todd and C. G. Tiefel. Such machines have a type carrier provided with word type forms of different lengths, and a rotary printing platen. The type carrier is first adjusted to set the desired word type form opposite the platen, after which a main operating mechanism is actuated to actuate the type carrier and thereby effect a rolling printing engagement of the type and platen. The co-operating faces of the type and platen are corrugated or otherwise roughened, and co-operate to break or disrupt the fibres of the paper as an incident to printing.

In the form of the present invention takes when applied to a machine of the Todd and Tiefel type, the faces of the type and platen may be left smooth, and the shredding or disrupting action upon the paper is performed by an auxiliary mechanism which comprises two differentially rotatable rollers, one above and the other below the work, and having their work-engaging faces corrugated or otherwise roughened to break or loosen the fibres as the work passes between them. Preferably these rollers are positioned to do their work in advance of the printing.

A differential mechanism is provided for driving one or the other of the rollers, preferably the upper one, directly by movement of the main operating mechanism to extents corresponding with the lengths of the words printed. This differential mechanism is controlled to determine the extent of movement of the driven roller by the same mechanism as is used in effecting the above-mentioned movement of the type carrier to set the various word type forms in printing relation with the platen.

In the form shown the differential mechanism comprises a set of toothed elements, one for each word type form, graduated to correspond with the lengths of the associated

type forms. Common to this set of toothed elements is a pinion or gear acting through suitable connections to drive the upper work-breaking roller. The construction is such that when the type selecting mechanism has been operated to set the desired word type form in position to co-operate with the platen, the corresponding toothed element will be in position to co-operate with the driven gear. The subsequent operation of the machine to effect engagement of the type and platen to print the desired word will cause the toothed element to act upon the driven gear and turn it a distance corresponding to the length of the type. This movement of the gear will be transmitted through the connections mentioned to the work-breaking roller.

The Todd and Tiefel machine has a central shaft 10 journaled at its ends in the case 11 of the machine. Secured to the shaft is a gear 12, Fig. 2, meshing with a pinion 13 secured to the inner end of a short shaft 14 journaled in a boss 15, Fig. 1, on the casing. Attached to the outer end of the shaft 14 is a handle 16 by means of which the shaft 14 may be turned. This movement of the shaft 14 is transmitted by the gears 13 and 12 to the shaft 10 and as the gears 13 and 12 are of the same size each turn of the handle 16 will result in a complete rotation of the shaft 10. A type carrier 17 is splined upon the shaft 10 so that it may be adjusted to different positions along the shaft but will turn with the shaft when the latter is rotated. The face of the type carrier is provided with a number of word type forms 18 of various lengths.

For the purpose of moving the carrier to different positions on the shaft there is provided a yoke 19, the ends of which are loose upon and surround the shaft 10 so that if the yoke is moved endwise of the shaft the type carrier is carried along. Near one end the yoke is provided with a handle 21, Fig. 3, integral with which is a pointer 22 co-operating with an index plate 23, Fig. 1, to guide the operator in adjusting the yoke and thereby the type carrier to different printing positions.

Under the type carrier is a platen wheel or disc 24, Figs. 3 and 6, rotatably supported between arms of a yoke 25 secured to a shaft 26 journaled at one end in the casing and at the other end in a cross bar 28 integral with the casing. Secured to the end of the shaft 26 is an arm 31, Fig. 5, having its upper end formed to co-operate with a cam 32 secured to the shaft 10. The configuration of the cam 32 is such that when the shaft 10 is rotated clockwise, Fig. 5, the lever 31 and shaft 26 will be rocked in the same direction against the tension of a spring 33. This will cause the platen 24

to be swung into the path of travel of the type form which has been set in printing relation to the platen and held stationary long enough to co-operate with the longest type form on the carrier. The platen is then released and the spring 32 swings it down out of the road so as not to interfere with the selecting movement of the carrier along the shaft 10.

As before stated, the type and platen may be left perfectly smooth when the present invention is employed, the function performed by the usual corrugated or roughened surfaces of the type and platen being performed by co-operating rollers which are constructed to break or disrupt the fibre of the material in advance of the printing. These rollers are positioned one above and one below the work-receiving slot and are separable to permit insertion of the work. Before any word can be printed the rollers are brought together to act upon the paper, and remain in that relation until after the printing of the desired inscription is completed and the rollers separated to permit removal of the paper.

The upper one of the rollers is designated by the numeral 35, Fig. 3, and is secured to a shaft 36, (see also Fig. 1), supported by brackets 37 attached to the machine case. The lower roller 38, Figs. 3 and 6, is loose upon a rod supported between the side arms of a yoke 39 attached to a rock shaft 40. This rock shaft is formed at its forward end, first toward the center line of the machine and then upward, the upwardly extending end being beveled as shown at 41, Fig. 2, to co-operate with the surface 42 on the type selecting yoke 19. When the type selecting mechanism is operated to set the pointer 22 opposite the word "Release" on the selecting dial, the surface 42 of the type selecting yoke will act upon the end of the rod 40 to rock the rod counter-clockwise, Fig. 3, against the tension of a spring (not shown), thereby lowering the roller 38 to permit insertion of the paper. When the pointer 22 is moved to any other position the tension of the spring is released and returns the roller 38 into engagement with the roller 35.

The faces of the rollers 35 and 38 may be corrugated or roughened according to any desired plan so that they will co-operate to disrupt the paper and permit the ready penetration of the ink. In order to insure firm engagement of the rollers there is provided a mechanism comprising an arm 45, Figs. 3 and 6, provided with a set screw 46 to engage the under side of an ear 47 on one of the side arms of the yoke 39. The arm 45 is connected by a link 48 with an arm 49 integral with the platen yoke 25. When the shaft 26 is rocked as above described, to carry the platen wheel 24 into printing po-

sition, the link 48 will rock the arm 45 and yoke 39 to hold the disrupting roller 38 in firm engagement with the upper roller 35.

Rigid with the rollers 35 and 38 respectively are rollers 52 and 53 having their engaging surfaces constructed to act upon the paper in the same way as do the surfaces in the rollers 35 and 38. The second pair of co-operating rollers will not only help to 10 keep the paper moving in a straight line, but will also disrupt or break the fibres of the paper in the line in which the payee's name is usually written on a check.

The mechanism for differentially driving 15 the roller 35, and, of course, the roller 53, distances corresponding to the length of the word printed, comprises a set of partial gears designated generally by the numeral 54. These partial gears are fast upon a 20 shaft 55; journaled at its ends in arms 56 extending from the end members of the type selecting yoke 19. A stiffening bar or rod 57 extends thru all of the toothed elements 54.

25 Rotation of the partial gears or elements 54 is effected when the handle 16 is turned to rotate the type carrier 17 into engagement with the platen 24 to print. For this purpose there is provided a gear 61 rigid 30 with the type carrier meshing with a pinion 62 rotatably mounted on the yoke 19 and which in turn meshes with a gear 63 rigid with the shaft 55 and elements 54. It is apparent that at each turn of the handle 16 35 the shaft 55 and the parts thereon will be rotated.

A shaft 64 rotatably mounted above the toothed elements 54 has fastened thereto a small gear 65. Near the other end of the 40 shaft 64 is another gear 66 meshing with an intermediate gear 67 which in turn meshes with a gear 68 loose upon the central shaft 10. The teeth of the gear 68 are at all times in engagement with the teeth of a smaller 45 gear 69 secured to the shaft 36 previously mentioned.

The toothed elements 54 are in alinement with and each with a single exception has a 50 number of teeth corresponding to the lengths of the associated type forms 18. When the type selecting yoke 19 is moved to position the desired type form 18 in operating relation with the platen 24, the corresponding toothed element 54 will be set in 55 alinement with the gear 65. Subsequent operation of the handle 16 to effect printing rotation of the type carrier will cause the shaft 64 to be driven an extent determined by the number of teeth on the positioned 60 element 54.

As stated above, there is one exception to 65 having the number of teeth on the elements 54 correspond with the lengths of the associated type forms. This exception is found in the element 541 in alinement with the

type form for printing the word "Exactly." In operating the machine shown in the drawings the word "Exactly" is printed first, with the words representing the amount following in the usual order. The 70 gear 541 at the "Exactly" position has a toothed portion considerably longer than the "Exactly" type form, the arrangement being such that almost immediately after the operation of the handle 16 is begun the 75 teeth of the gear 541 will begin to rotate the shaft 36 and roller 35. As a consequence, the paper will be disrupted and fed far enough for the disrupted surface to be in position to receive the impression by the 80 time the "Exactly" type form engages the platen.

The gearing above described is so proportioned that the periphery of the roller 35 and, of course, the associated roller 52, will 85 move at the same peripheral speed as the type, when the type pass across the platen 24. As a result of this construction, the work of the rollers 35 and 38 is performed in proper time relation with the printing action 90 of the type and platen, and the paper is relieved from any strain or stress between the printing point and the point where it is disrupted.

In order to insure holding the differential 95 gearing in proper position to be engaged by the teeth on the different elements 54, there is provided a means for locking the shaft 36 against movement between printing operations. As shown in Fig. 5, the arm 31 previously mentioned is provided with an extension 71, carrying a stud 72 normally in engagement with the teeth of the gear 69. When the arm 31 is rocked by the cam 32, as previously described, the stud 72 will be 100 disengaged from the gear 69, thereby freeing the gear and connected parts for rotation. When the cam allows the arm 31 to return to its normal position, the stud will 105 re-engage the gear to aline and hold the 110 various parts in proper position ready for the next operation.

The inking mechanism may, of course, be of any suitable form, but in the drawings it is shown as comprising rollers 73 and 731, 115 supplied with ink of one color, and rollers 74 and 741 supplied with ink of a different color. As the type carrier 17 is rotated, the type contact these rollers to replenish the supply of ink on the type.

In describing the invention it has incidentally been necessary to point out the different steps of the operation, so it is believed that the statement of the operation usual at this point may be omitted.

While the embodiment of the invention herein shown and described is admirably adapted to fulfill the objects primarily stated, it is not the desire to be limited to this one embodiment, as the invention 130

is capable of various modifications and changes, all coming within the scope of the claims which follow.

What is claimed is:—

5. 1. In a machine of the class described, the combination with a printing couple, of mechanism comprising a prime mover for actuating the printing couple, devices comprising a pair of rotary elements, one above and one 10 below the work, for breaking the work and feeding it to the printing couple, differential mechanism driven by the prime mover for differentially rotating one of said elements, and manipulative devices controlling the differential mechanism.

2. In a machine of the class described, the combination with a printing couple, of mechanism comprising a prime mover for actuating the printing couple to effect printing, devices comprising a pair of rotary elements, one above and one below the work, for breaking the work and feeding it to the printing couple, differential mechanism driven by the prime mover for differentially 20 and positively driving the upper of the rotary elements, and manipulative devices controlling the differential mechanism.

3. In a machine of the class described, the combination with a printing couple constructed to print words of different lengths, of manipulative devices for determining the word to be printed, a prime mover and connections for effecting printing operation of the couple, devices comprising a pair of rotary elements, one above and one below the work, constructed to break the work and feed same to the printing couple, and differential gearing controlled by the aforesaid manipulative devices and actuated by the 30 prime mover for differentially driving one of said rotary elements.

4. In a machine of the class described, the combination with a printing couple constructed to print words of different lengths 45 and feed the work corresponding distances, of manipulative devices for determining the word to be printed, a prime mover and connections for effecting the printing and feeding operation of the printing couple, devices comprising a pair of rotary elements, one above and one below the work, constructed to break the work and feed same to the printing couple, and differential gearing controlled by the aforesaid manipulative 50 device and actuated by the prime mover for differentially and positively driving the upper of said rotary elements.

5. In a machine of the class described, the combination with a printing couple constructed to print words of different lengths 60 and feed the work corresponding distances, of means comprising a selector for determining the word to be printed, operating mechanism for effecting the printing and feeding 65 movement of the printing couple, devices

comprising a pair of rollers constructed to break the work and feed same to the printing couple, differential gearing controlled by the aforesaid selector and driven by the operating mechanism for driving one of said 70 rollers extents corresponding to the lengths of the words printed, and a lock controlled by the operating mechanism for holding the driven roller against movement between printing and feeding operations. 75

6. In a machine of the class described, the combination with a printing couple constructed to print words of different lengths, of means for operating the couple to print any one of the words, paper rupturing devices comprising a pair of co-operating roughened rollers adjacent the printing couple, and devices controlled by the aforesaid means for driving the upper and thereby the lower of said rollers different distances at 80 each operation of said means to rupture the work through distances corresponding to the lengths of the words printed. 85

7. In a machine of the class described, the combination with a type carrier provided 90 with type forms of different lengths, of a platen, a set of driving gears graduated in length to correspond with the lengths of the various type forms, a driven gear common to the driving gears, means for effecting 95 relative movements of the type carrier and platen to determine the form to be printed from and of the driving gears and driven gear to determine which driving gear is to be effective, paper rupturing devices adjacent the type carrier and platen actuated by the driven gear to rupture the work and feed same to printing position, operating mechanism for bringing the type carriers and platen together to print and for actuating 105 the selected driving gear. 100

8. In a machine of the class described, the combination with a type carrier provided with type forms of different lengths of a platen, a set of driving gears graduated in 110 length to correspond with the lengths of the type forms, a driven gear common to the driving gears, means for adjusting the type carrier to set any desired type form in printing relation with the platen and any driving gear in operating relation with the driven gear, paper rupturing devices adjacent the type carrier and platen actuated by the driven gear to rupture the work and feed same to printing position, and operating 115 mechanism for effecting printing movement of the type carrier and driving movement of the driving gears. 120

9. In a machine of the class described, the combination with a printing couple, of mechanism comprising a prime mover for actuating the printing couple, devices comprising a pair of differentially movable elements, one above and the other below the work, having co-operating faces constructed 125 130

to break the work, differential mechanism connected for actuation by the prime mover for effecting differential movement of the upper element and thereby a corresponding 5 movement of the lower element, and manipulative devices controlling the differential mechanism.

10. In a machine of the class described, the combination with a printing couple of mechanism comprising a prime mover for actuating the printing couple, devices comprising a pair of rotary elements, one above and one below the work for breaking the work and feeding it to the printing couple, 15 mechanism actuated by the prime mover for differentially rotating said elements, said elements having a relative movement to permit insertion and removal of the work, manually operative devices for effecting said 20 relative movement, and mechanism controlled by the prime mover for preventing such relative movement during the disrupting and feeding operation.

11. In a machine of the class described, 25 the combination with a type carrier of a platen movable toward the type carrier in printing, operating devices for effecting the movement of the platen, devices comprising a pair rotary elements, one above and one 30 below the work for breaking the work and feeding it to the printing couple, mechanism actuated by said operating devices for differentially rotating said elements, said elements having a relative movement to permit 35 insertion and removal of the work, manually operative devices for effecting said relative movement, and devices rendered effective by movement of the platen operating devices for preventing said relative movement 40 during the disrupting and feeding operation.

12. In a machine of the class described,

the combination with a printing couple, of mechanism comprising a prime mover for actuating the printing couple, devices comprising a pair of co-operating elements, one above and the other below the work, for breaking the work along the printing line, differential mechanism actuated by the prime mover for differentially and positively 5 operating said elements, and manipulative devices controlling the differential mechanism.

13. In a machine of the class described, the combination with a printing couple, of mechanism comprising a prime mover for actuating the printing couple, a pair of devices, one above and one below the work, for breaking the work and feeding it to the printing couple, mechanism including differential devices driven by the prime mover for imparting paper-breaking and feeding movements to the aforesaid elements, and manipulative means for controlling the differential devices and thereby the extent of 6 the paper feed.

14. In a machine of the class described, the combination with a type carrier, of a rock shaft, a platen secured to the rock shaft, means for rocking the shaft to move 7 the platen in and out of printing engagement with the type, a pair of elements, one above and one below the work, for breaking the work and feeding it toward the platen and type, said elements having a relative 7 movement to permit insertion and removal of the work, manually operative devices for effecting said relative movement, and means connected for actuation by the platen rock shaft for preventing said relative movement 8 during the disrupting and feeding operation.

In testimony whereof I affix my signature.

WALTER B. PAYNE.
